DESIGN FOR A COMBINATION DRESS

Anna Naubert, Chicago, Ill.

Application November 12, 1938, Serial No. 81,049

Term of patent 3½ years

To all whom it may concern:

Be it known that I, Anna Naubert, a citizen of the United States, residing at Chicago, in the county of Cook and State of Illinois, have invented a new, original, and ornamental Design for a Combination Dress, for which the following is a specification, reference being had to the accompanying drawing, forming part thereof, wherein

Fig. I is a front view of a combination dress, showing my new design.

Fig. II is the rear view of a combination dress shown in Fig. I.

Fig. III is a front view of the combination dress shown in Fig. I, showing the detachable overskirt partially removed; and

Fig. IV is a rear view of the combination dress shown in Fig. I, showing the detachable overskirt removed.

I claim:

The ornamental design for a combination dress, substantially as shown.

ANNA NAUBERT.
